UNITED STATES PATENT OFFICE.

PHILETIS T. BARKER, OF IMBODEN, VIRGINIA.

WRENCH.

1,001,605.

Specification of Letters Patent. Patented Aug. 29, 1911.

Application filed August 12, 1910. Serial No. 576,887.

To all whom it may concern:

Be it known that I, PHILETIS T. BARKER, a citizen of the United States, residing at Imboden, in the county of Wise and State 5 of Virginia, have invented certain new and useful Improvements in Wrenches, of which the following is a specification.

My invention relates to new and useful improvements in wrenches.

10 An important object of this invention is to provide a wrench, the stationary jaw of which may be readily adjusted so that said wrench may be employed to grip different sizes of work.

15 A further object of this invention is to provide a wrench particularly adapted to grip the flanges of a pipe, whereby two pipes provided with such flanges may be readily secured together.

20 A further object of this invention is to provide a wrench of the above character, which is formed of few and simple parts and which is cheap to manufacture and positive in its operation.

25 Other objects and advantages of this invention will be apparent hereinafter.

In the accompanying drawings forming a part of this specification and in which like numerals are employed to designate like 30 parts throughout the same, Figure 1 is a side view of the wrench, Fig. 2 is a plan view of the same, Fig. 3 is a longitudinal sectional view through the body portion of the wrench, and Fig. 4 is a perspective view 35 of the stationary jaw.

In the drawings, wherein is illustrated a preferred embodiment of my invention, the numeral 5 designates the body portion of the wrench, comprising a pair of spaced 40 substantially U-shaped members 6, which are connected at their ends, as shown at 7 and 8. The body portion is preferably stamped from sheet-metal and bent upon itself to form the substantially U-shaped members 6. An operating lever 9 is disposed between the members 6 near one end of the body portion, as shown, and this lever is pivotally connected with said members 6 by means of a bolt 10. The lever 9 45

50 has a jaw 11 formed upon its inner end and preferably cast integral therewith, which jaw is provided with a groove 12 extending longitudinally thereof for receiving a tongue 13 of a removable hard steel plate 14. This 55 plate is held upon the jaw 11, which may be termed the movable jaw, by means of pins

15, or the like, disposed within suitable openings formed through the tongue 13. The plate 14 is provided with teeth 16 for gripping the work.

Arranged in opposition to and adapted to coöperate with the movable jaw 11, is a stationary jaw 17, having a shank 18, which is provided, as shown, with ratchet-teeth 19. These ratchet-teeth are formed upon the 60 upper side of the shank 18 and are engaged by a pawl 20, which is pivotally mounted upon a transverse bolt 21 connecting corresponding ends of the members 6. A coil spring 22 is provided, which has one end 65 thereof suitably connected with one of the members 6 and its opposite end suitably connected with the pawl 20, whereby said pawl is urged into engagement with said ratchet-teeth. This pawl is also provided 70 with a handle 23, whereby the same may be moved out of engagement with the ratchet-teeth 19. The shank 18 is slidably mounted upon the section 7, and owing to the inclination of the ratchet-teeth 19, it is obvious that 75 the jaw 17 and shank 18 may be moved toward the jaw 11, and that the pawl 20 will prevent their movement in an opposite direction. The stationary jaw 17 is thus adjustable to or away from the movable jaw 80 85 90 95

11 and may be locked in such adjusted position by the pawl 20. The stationary jaw 17 is provided with a groove 24 for the reception of a tongue 25 formed upon a hard steel plate 26. This plate 26 is secured upon the stationary jaw 17 by means of pins 27, which are disposed within suitable openings formed through the tongue 25. The inner side of the plate 26 is provided with teeth 28, as shown.

In the use of my wrench, the lever 9 is raised to the position illustrated in Fig. 1, the work is then placed between the jaws 11 and 17 and the jaw 17 adjusted so that both of the jaws 11 and 17 engage said work. It 100 is obvious that when pressure is exerted upon the lever 9 the movable jaw 11 will grip the work.

I wish it understood that the form of my invention herewith shown and described is 105 to be taken as a preferred example of the same, and that certain changes in the size, shape and arrangement of parts may be resorted to without departing from the spirit of my invention or the scope of the subjoined claim.

Having thus fully described my invention

what I claim as new and desire to secure by Letters Patent, is:—

In a wrench of the character described, a U-shaped body portion, a shank provided 5 with teeth upon one longitudinal edge thereof and movably mounted through one end portion of said U-shaped body portion, said shank extending substantially parallel with the middle portion of said U-shaped body 10 portion, a pawl pivotally connected with said end portion and movable into and out of engagement with said teeth, a spring to engage said pawl, a jaw carried by said shank, an operating lever pivotally con-

nected with the opposite end portion of said 15 U-shaped body portion, and a jaw carried by said operating lever, said operating lever being adapted to be oscillated to assume a position parallel to the said shank, whereby the pressure is exerted upon the lever and 20 shank in a longitudinal direction with relation thereto.

In testimony whereof I affix my signature in presence of two witnesses.

PHILETIS T. BARKER.
